UNITED STATES PATENT OFFICE.

WILLIAM D. BUSS, OF CLEVELAND, OHIO, ASSIGNOR TO THE HAMMOND MANUFACTURING COMPANY, OF CLEVELAND, OHIO, A CORPORATION OF OHIO.

POLISHING OR LIKE MACHINE.

Application filed June 13, 1924. Serial No. 719,777.

This invention relates to improvements in polishing and like machines, particularly of the type embodying an operating motor and one or more individually controlled shafts driven thereby and upon which the polishing or grinding disks may be removably mounted. In the present case, two aligned separate shafts are shown as having driving connection with a continuously running electric motor, and separate control means are provided for starting and stopping each shaft.

One object of this invention is to provide braking means for promptly stopping rotation of either shaft when freed from its motor drive, so as to prevent idling of the shaft. This braking means is operatively connected with the control means for the driving connection between the motor and shaft, so that when the driving connection is rendered ineffective the braking means becomes effective; and when the driving connection is effected, the braking action is relieved.

Another object is to provide means for positively and at will locking each shaft against rotation so as to facilitate the removal and exchange or renewal of the polishing or grinding disks.

A further object of this invention is to provide one means for controlling both the driving connection and the locking means in such a manner that if the driving connection is rendered ineffective the locking means is advanced toward locking position and locking action can then readily be effected by slight further movement after the shaft has been brought to rest.

This invention comprises also the provision of a single actuating or control means for the driving connection, the braking means and the locking means, all of which therefore operate in harmonious relation with each other.

Other objects will appear from the following description and claims when considered with the accompanying drawing.

Fig. 1 shows my improved device in front elevation with part of the casing broken away and parts in section; Fig. 2 is an end view with part of the casing broken away and other parts in section; Fig. 3 is a detail sectional view taken on line 3—3 of Fig. 2; and Fig. 4 is a similar view of a modification.

Enclosed within the casing 1 is the electric motor 2 which is provided on both ends of its rotor shaft with driving pulleys 3 the belts 4 of which extend around the driven pulleys 5 fixed upon the separate shafts 6 60 in the upper part of the casing. Both ends of the machine are alike and the description of one will suffice for both. Shafts 6 are provided with separate duplicate driving and control mechanisms and can be operated and controlled independently of each other. Each shaft is provided on its outer end portion with fixed and adjustable collars 7, 8, the latter of which is clamped against the polishing disk by the nut 9. 70 Belt 4 has sufficient slack to permit it to slip and thereby prevent driving relation between the motor and the shaft when desired. This slack may be taken up at will by means of an idle pulley 10 on an arm 11 rockably 75 mounted in a wall of the casing and controlled by a lever arm 12 on the outside of the casing. The belt is shown in slack or idle condition in Fig. 2, but upon movement of the lever arm 12 to the right, pulley 10 80 tightens the belt and thereby effects driving relation between the motor and shaft 6. Lever arm 12 may be held in any position to which it is moved by the pawl 13 actuated by lever 14 and yieldably engaged with the 85 notched segment 13^a mounted on the casing wall.

When pulley 10 is moved away from the belt the shaft 6 will continue to run idly until friction brings it to rest. To bring it 90 to rest promptly I have provided a brake 15 the resilient lining 16 of which is adapted to engage the drum 15^a on shaft 6. Brake 15 is mounted upon the upper end of a rod 17 working in a barrel 18 against compression spring 21 and having a guiding pin 19 working in the slot 20 to provide lost motion and prevent relative rotation between rod and barrel. The lower end of the barrel 18 has pivotal connection at 23 with the 100 arm 24 on shaft 25 of the arm 12. These parts are so constructed and arranged that upon movement of the lever 12 to the right, Fig. 2, for effecting driving relation between the motor and shaft 6 the brake is 105 simultaneously rendered ineffective by downward movement of the cylinder 18 which drags the rod 17 downwardly therewith by the pin and slot connection therebetween.

Lever arm 12 may also be provided with a 110

locking or latching pin 26 held by a spring 27 against the side of segment 13^a which is provided with recess or opening 28 adapted to receive a manually releasable pin 26 to 5 maintain the lever arm 12 in any predetermined position corresponding to the effective position of the brake. Pin 26 of course may be readily released from its locking position by pulling the same outwardly against the 10 tension of the spring 27.

Means are also provided for temporarily locking shaft 6 against rotation to maintain it in fixed position while the polishing disks are removed and renewed or 15 changed. The same drum 15^a which is engaged by the brake shoe, is provided with a plurality of radially extending openings 29, four being here shown arranged at 90°. These openings are adapted to receive the 20 upper end of a pin 30 which is fixedly secured by a strap 31 to the upper end of cylinder 18 and is guided by a bracket 33 on the casing wall. Pin 30 also extends through a side portion 34 of the brake shoe 25 15. Upon upward movement of the cylinder 18, the rod 30 is also moved upwardly into engagement with one of the openings 29 in the manner and for the purpose now to be explained.

30 As above stated, the parts as shown in the present illustration are in idle position; that is, driving relation between the motor and shaft 6 is broken. The brake is fully applied to the brake drum to bring shaft 6 35 to rest, and pin 30 is in engagement with one of the openings 29 to hold or lock shaft 6 against rotation in either direction. When the driving relation is again established between the motor and shaft 6, the pulley 10 40 takes up the belt slack and lever 12 occupies a position to the right of that illustrated in Fig. 2. Also, the brake shoe is away from the brake drum and pin 30 is out of engagement with the opening 29.

45 When it is desired to stop operation of the shaft 6 for any purpose, the lever 12 is moved to the left to bring the pin 26 into engagement with a recess 28, such movement being sufficient to permit the belt to become 50 slack and ineffective and also to move the cylinder 18 upwardly. Spring 21 is confined in cylinder 18 with some inherent compression and as soon as the upper end of slot 20 leaves the pin 19 the full compression effect of spring 21 is applied through the 55 brake to the brake drum, bringing shaft 6 to rest before the upper end of rod 30 reaches the drum.

60 Whenever the operator desires to temporarily lock the shaft against rotation, he moves the lever 12 farther to the left, Fig. 2, until the pin 26 snaps into a second recess 28^a, such further operation causing stem 30 to enter one of the openings 29 65 which in the meantime has been brought

into proper registering position by manually turning the shaft 6. After exchange or renewal of the polishing or grinding disks, the machine may be set into operation by withdrawing the pin 26 from the recess 28^a 70 and moving lever 12 to the right to effect the driving relation between the motor and shaft 6. Simultaneously pin 30 is withdrawn from the opening 29 and the brake shoe is relieved from engagement with the 75 drum so that shaft 6 is at once driven. Such manipulation of lever 12 moves the cylinder 18 downwardly permitting spring 21 to expand and move pin 19 to the upper end of the slot 20 and positively lowers the 80 brake-shoe away from the brake drum. Lever 12 is then held in its right-hand position by the pawl 13.

In Fig. 4 I have shown a modified form of locking means for lever 12. Here I have 85 provided recesses 35 and 35^a which are adapted to receive the tapered end of a yielding pin 36. The handle 12 is moved to the right or to the left, as the case may be, whereupon the tapered nose of the pin 90 rides up out of the tapered depression or seat. Instead of a separate pin 36 and spring 37, the lever arm 12 may itself be formed with an integral projection and the lever arm may be sufficiently resilient that 95 such projection may be snapped into and out of such depressions or seats in the same manner as just now described.

What I claim is:

1. In a machine of the class described, 100 the combination of a rotatable shaft, operative means for said shaft, disconnectible operative connecting means between said operating means and shaft, braking means for said shaft, a single controlling means for 105 said connecting means and braking means, and means for holding said controlling means in any adjusted position.

2. In a machine of the class described, 110 the combination of a rotatable shaft, operating means therefor, disconnectible operative connecting means between said operating means and said shaft, braking means for said shaft, controlling means for said connecting means and said braking means, 115 and means for automatically holding said controlling means in any adjusted position.

3. In a machine of the class described, 120 the combination of a rotatable shaft, means for removably securing an attachment to said shaft, means for operating said shaft, and means for temporarily locking said shaft against rotation in both directions so as to facilitate the connection or disconnection of said attachment.

4. In a machine of the class described, 125 the combination of a rotatable shaft structure having an opening therein, means for removably securing an attachment to said shaft structure, and means adapted to en- 130

- gage in the opening of said shaft structure for locking the same against rotation so as to facilitate the connection or disconnection of said attachment.

5. In a machine of the class described, the combination of a rotatable shaft, means for removably securing an attachment to said shaft, means for operating said shaft, means for temporarily locking said shaft against rotation so as to facilitate the connection or disconnection of said attachment, and means for actuating said locking means upon stopping of said shaft.

6. In a machine of the class described, the combination of a rotatable shaft, means for removably securing an attachment to said shaft, means for operating said shaft, means for temporarily locking said shaft against rotation so as to facilitate the connection or disconnection of said attachment, and means for actuating said locking means upon stopping of said shaft and for releasing the same upon starting of the shaft.

7. In a machine of the class described, the combination of a rotatable shaft, means for removably securing an attachment to said shaft, means for operating said shaft, controlling means for rendering said operating means effective or ineffective, means for temporarily locking said shaft against rotation so as to facilitate the connection or disconnection of said attachment, and a single means for actuating said controlling means and said locking means.

8. In a machine of the class described, the combination of a rotatable shaft, means for removably securing an attachment to said shaft, means for operating said shaft, controlling means for rendering said operating means effective or ineffective, means for temporarily locking said shaft against rotation so as to facilitate the connection or disconnection of said attachment, and means for simultaneously actuating said controlling means and said locking means.

9. In a machine of the class described, the combination of a rotatable shaft, disconnection operating means therefor, braking means for said shaft, means for removably securing an attachment to said shaft, means for temporarily locking said shaft against rotation so as to facilitate the connection or disconnection of said attachment, and means for simultaneously actuating said braking means and said locking means.

10. In a machine of the class described, the combination of a rotatable shaft, means for removably securing an attachment to said shaft, means for operating said shaft, controlling means for rendering said operating means effective or ineffective, means for temporarily locking said shaft against rotation so as to facilitate the connection or disconnection of said attachment, a braking means for said shaft, and means for simultaneously actuating said controlling means, said braking means and said locking means.

11. In a machine of the class described, the combination of a rotatable shaft, operating means therefor, braking means for said shaft, means for removably securing an attachment to said shaft, means for temporarily locking said shaft against rotation so as to facilitate the connection or disconnection of said attachment, means for actuating said braking means and said locking means, and means for maintaining said actuating means in two positions, in one of which positions said braking means is effective and said locking means is ineffective, and in the other of said positions said locking means is effective.

12. In a machine of the class described, the combination of a rotatable shaft, operating means therefor, braking means for said shaft, means for removably securing an attachment to said shaft, means for temporarily locking said shaft against rotation so as to facilitate the connection or disconnection of said attachment, a single actuating means for said braking means and locking means, and said braking means including a yieldable part, whereby said locking means may be applied after application of said braking means.

13. In a machine of the class described, the combination of a rotatable shaft, operating means therefor, braking means for said shaft, means for removably securing an attachment to said shaft, means for temporarily locking said shaft against rotation so as to facilitate the connection or disconnection of said attachment, said shaft being provided with portions adapted for engagement by said braking means and locking means, respectively, actuating means for effecting engagement of said braking means and locking means with their respective portion, and a yieldable connection between said braking means and said actuating means, whereby said braking means may be applied gradually.

14. In a machine of the class described, the combination of a rotatable shaft, operating means therefor, braking means for said shaft, means for removably securing an attachment to said shaft, means for temporarily locking said shaft against rotation so as to facilitate the connection or disconnection of said attachment, a single actuating means for said braking means and locking means, and spring and pin-and-slot connection between said braking means and actuating means.

In testimony whereof I hereby affix my signature.

In testimony whereof I hereby affix my ¹²⁵ signature.

WILLIAM D. BUSS,
